UNITED STATES PATENT OFFICE.

JOSEPH N. MAHONEY AND JOHN B. MACNEILL, OF WILKINSBURG, PENNSYLVANIA,
ASSIGNORS TO WESTINGHOUSE ELECTRIC AND MANUFACTURING COMPANY, A
CORPORATION OF PENNSYLVANIA.

CIRCUIT-INTERRUPTER.

1,386,011.

Specification of Letters Patent. Patented Aug. 2, 1921.

Application filed May 15, 1917. Serial No. 168,676.

To all whom it may concern:

Be it known that we, JOSEPH N. MAHONEY, a citizen of the United States, and a resident of Wilkinsburg, in the county of Allegheny and State of Pennsylvania, and JOHN B. MACNEILL, a citizen of the United States, and a resident of Wilkinsburg, in the county of Allegheny and State of Pennsylvania, have invented a new and useful Improvement 10 in Circuit-Interrupters, of which the following is a specification.

Our invention relates to circuit interrupters and particularly to interrupters having a plurality of steps in their operation.

15 One object of our invention is to provide a single-operating-rod circuit interrupter that shall have means for obtaining an interval of time between the operation of its main and auxiliary contact members.

20 Another object of our invention is to provide a resistance type of circuit interrupter that shall have a minimum number of stationary contact terminals.

Another object of our invention is to provide 25 an interrupter that shall be adapted to be closed slowly and to have its final opening occur after the movable operating rod has attained its maximum speed.

A further object of our invention is to provide 30 a circuit interrupter of the above indicated character that shall be compact in design and efficient in its operation.

In practising our invention, we provide a circuit interrupter having three stationary 35 terminal members two of which are provided with single contact members and the other one of which is provided with a double contact member. A single operating rod is provided with a main bridging contact member at one end that is adapted to engage one 40 of the single and one of the double contact members. Two auxiliary contact members are pivotally mounted on the operating rod above the main bridging member and at an angle thereto. The auxiliary contact members are yieldingly restrained in their upper 45 positions by springs and are adapted to engage one of the single and one of the double contact members an interval of time before the main contact members are engaged.

Such a circuit interrupter is applicable either for inserting resistance in a circuit before the circuit is entirely closed and opened, respectively, or to cause the circuit

to be opened and closed at a plurality of 55 points to relieve the disturbances incident to the switching thereof.

In the accompanying drawings, Figure 1 is a side elevational view, with parts broken away, of a circuit interrupter embodying 60 our invention; Fig. 2 is a top plan view of the circuit interrupter shown in Fig. 1; Figs. 3, 4 and 5 are detail views of the stationary terminal members of the interrupter shown in Figs. 1 and 2; Fig. 6 is a detail 65 plan view of the movable contact members shown in Fig. 1; Fig. 7 is a detail elevational view of the main movable contact members; and Fig. 8 is a detail elevational view of the auxiliary contact members embodying our invention. 70

The circuit interrupter 1 comprises, in general, a supporting base 2, an oil-containing receptacle 3, a pneumatic operating device 4, stationary terminal members 5, 6 and 7, a movable operating rod 8, a main movable bridging member 9, auxiliary pivotally mounted members 10 and 11 and a linkage mechanism 12 for operatively connecting the rod 8 to the operating device 4. 80

The stationary terminal members 5, 6 and 7 are so mounted on the supporting member 2 that the terminal member 7 is equidistant from the members 5 and 6. The terminal member 5 is provided with a single 85 stationary contact member 13 and the stationary terminal member 6 is provided with a main contact member 14 and an arcing tip or auxiliary contact member 15. The main contact member 14 is resiliently supported 90 by the terminal member 6 and is adapted to be normally under tension in order that the stress on the same will be evenly distributed over its entire contact surface when its corresponding movable contact member 95 is brought into engagement therewith. The contact members 14 and 15 do not form a part of our present invention except in so far as they coöperate with other means to obtain the desired results and are clearly shown 100 and described in Patent No. 1,323,300, for circuit interrupter, issued Dec. 2, 1919, to J. N. Mahoney and assigned to the Westinghouse Electric and Manufacturing Company. The stationary terminal member 7 is 105 provided with a yoke member 16 upon one end of which is mounted a stationary contact member 17 and upon the other end of

which is mounted a main contact member 18 and an arcing tip or auxiliary contact member 19. The contact members 18 and 19 are similar to contact members 14 and 15 and 5 need not be further described.

The main bridging member 9 is secured to the lower end of the rod 8 and comprises two main contact members 20 and 21 and two arcing tips or auxiliary contact members 22 10 and 23, the contact members 20 and 22 being disposed at one end of the member 9 and the members 21 and 23 being disposed at the other end thereof. The movable contact members 20 and 22 are adapted to engage 15 the stationary contact members 14 and 15, respectively, and the movable contact members 21 and 23 are adapted to engage the said stationary contact members 18 and 19, respectively. The two auxiliary members 10 20 and 11 are pivotally mounted by means of a pin 24 on the rod 8 at a point above the bridging member 9 and they form an angle with respect to the member 9. A contact member 25, that is adapted to engage the 25 stationary contact member 13, is mounted on the member 10 and a contact member 26, that is adapted to engage the stationary contact member 17, is mounted on the member 11. Springs 27 and 28 are disposed between 30 a projection 29 on the member 10 and a portion of the rod 8 for the purpose of holding the member 10 normally in position shown in Fig. 8 of the drawings. Similarly, springs 30 and 31 are disposed between a projection 35 32 on the member 11 and the rod 8 to hold the contact member 26 in the position shown in Fig. 8 of the drawings. Conductors 33 are connected between the contact members 25 and 26 for the purpose of causing the members 10 and 11 to constitute a bridging member 40 between the stationary contact members 13 and 17 under predetermined conditions.

One conductor 34 of the circuit to be protected is connected to the terminal 6 and the 45 other conductor 35 of the circuit is connected to the terminal 7. A resistor or other current limiting device 36 is connected between the terminals 5 and 6 if it is desired that the interrupter 1 be adapted to insert a current 50 limiting medium in circuit before the circuit is finally closed and opened, respectively. However, if it is desired that the interrupter 1 constitute a means for interrupting a circuit at a number of points, the resistor 36 55 may be omitted.

If it is desired to complete the circuit between the conductors 34 and 35, the operating device 4 is energized by the admission of some form of fluid, such as air, and the 60 rod 8 is moved upwardly by reason of the operation of the linkage mechanism 12. When the rod 8 has moved a relatively short distance upwardly, the contact members 25 and 26 engage the stationary contact members 13 and 17 upon the terminal members 5

and 7. This completes a circuit from the conductor 34 through the resistor 36, the terminal 5, the stationary contact member 13, the movable contact member 25, the conductors 33, the movable contact member 26, 70 the stationary contact member 17 and the terminal 7 to the conductor 35. When this circuit is completed, the rush of current will be impeded because of the insertion of the resistor 36, and this retarding action of the 75 current will continue as the rod 8 moves upwardly.

Since the members 10 and 11 are pivotally mounted on the rod 8, further movement of the same will cause the springs 27 and 28, 30 80 and 31 to be compressed and the members 10 and 11 to move downwardly to the positions shown in Fig. 1 of the drawings. While the members 10 and 11 are being moved downwardly, the contact members 25 and 26 continue in sliding engagement with the stationary contact members 13 and 17, respectively. After the members 10 and 11 have almost reached the position shown in Fig. 1, the arcing contact members 22 and 23 engage 90 the arcing contact members 15 and 19, respectively. Further movement of the rod 8 compresses the springs 37 and 38 of the arcing contact members 15 and 19 and the main movable contact members 20 and 21 engage 95 the main stationary contact members 14 and 18 and thus complete the circuit from the conductor 34 through the terminal member 6, the contact members 14 and 20, the bridging member 9, contact members 21 and 18, 100 and the terminal 7 to the other conductor 35 of the circuit to be protected. It will thus be seen that the final closure of the interrupter 1 is relatively slow, and the disturbance of the circuit incident to the closure of the same 105 is obviated.

When it is desired to open the interrupter, the linkage mechanism 12 is released and the rod 8 is moved downwardly. The main contact members 20 and 21 disengage the contact members 14 and 18, followed after an interval of time by the disengagement of the arcing contact members 22 and 23 and 15 and 19, respectively. After the rod 8 has reached its maximum acceleration by reason of the 110 force of gravity and the expansion of the springs 27, 28, 30 and 31, the members 10 and 11 assume the positions shown in Fig. 8 of the drawings and the contact members 25 and 26 disengage the stationary contact 115 members 13 and 17. Thus, the final opening of the interrupter 1 is obtained while the operating mechanism is traveling at its greatest speed, and, consequently, the final interruption will be accomplished in a relatively quick time to thereby interrupt the circuit without undue disturbance therein.

By the use of our invention only a single operating rod is necessary to obtain the sequential operation of the main and aux- 125 130

iliary contact members and a minimum number of terminal members is required. Thus, the cost of construction is materially reduced over that of resistance types of interrupters 5 heretofore constructed, and a relatively compact and efficient device is obtained.

We do not limit our invention to the particular arrangements illustrated as various modifications may be made therein without 10 departing from the spirit and scope of the invention as set forth in the appended claims.

We claim as our invention:

1. In a circuit interrupter, the combination 15 with a single movable member having relatively movable contact members mounted thereon and angularly disposed with respect to each other, of three stationary terminal members, single contact members 20 mounted on two of the terminal members, and a double contact member mounted on the other terminal member, said stationary contact members being engaged by the movable contact members.

25 2. In a circuit interrupter, the combination with a single operating rod having four contact members mounted thereon and angularly disposed with respect to each other, of three stationary terminal 30 members, single contact members mounted on two of the terminal members, and a double contact member mounted on the other terminal member, said stationary contact members being adapted to be engaged by 35 the respective movable contact members.

3. In a circuit interrupter, the combination 40 with a single actuating rod, two bridging contact members mounted thereon, of three stationary contact terminals, single 45 contact members mounted on two terminals, and a double contact member mounted on the other terminal, said bridging members being adapted to engage the stationary contact members.

45 4. In a circuit interrupter, the combination with a single actuating rod, of a bridging contact member mounted at one end thereof, two oppositely disposed contact members pivotally mounted on the rod at 50 substantially right angles to the bridging member, and means for yieldingly maintaining the oppositely disposed contact members in predetermined positions.

5. In a circuit interrupter, the combination 55 with a single actuating rod, of a bridging contact member mounted at one end thereof, two oppositely disposed contact

members pivotally mounted on the rod and forming an angle with respect to the bridging contact member, and means for yieldingly maintaining the said contact members in predetermined positions with respect to the rod.

6. In a circuit interrupter, the combination 60 with a single movable operating rod having two main contact members and two resiliently mounted contact members thereon, of two single stationary contact members, and a double stationary contact member, said main contact member being positioned to engage one of the single and one of the double stationary contact members an interval of time after the resiliently mounted contact members engage the other single and the other double stationary contact 65 members.

7. In a circuit interrupter, the combination 70 with three stationary terminal members and a single movable member, of a main bridging contact member mounted on the single movable member, and an auxiliary bridging contact member mounted above the main bridging member on the movable member at substantially right angles to the main bridging member, said movable contact members being positioned to engage the 75 stationary terminal members in a predetermined sequence.

8. In combination, a circuit interrupter 80 comprising a plurality of movable bridging contact structures, a single operating member therefor, a pair of stationary contact members for coöperation with each bridging structure, and a current-retarding device connected between one contact member of 85 one of said pairs of stationary contact members and one contact member of another of said pairs thereof.

9. A circuit interrupter comprising a plurality of movable bridging contact structures, a single operating member therefor and a pair of stationary contact members for coöperation with each bridging structure, said bridging structures and said stationary contact members being constructed 100 to constitute a plurality of parallel circuit paths and to interrupt each of said paths at a plurality of positions.

In testimony whereof, we have hereunto 105 subscribed our names this 30th day of April, 1917.

JOSEPH N. MAHONEY.
JOHN B. MACNEILL.
